US00D598423S

(12) **United States Design Patent**
Lamarche et al.

(10) **Patent No.:** **US D598,423 S**
(45) **Date of Patent:** **** Aug. 18, 2009**

(54) **KEY FOB**

(76) Inventors: **Patricia Lamarche**, 2277 SW. 131st Ter., Miramar, FL (US) 33027; **Oscar Lamarche**, 2277 SW. 131st Ter., Miramar, FL (US) 33027

(**) Term: **14 Years**

(21) Appl. No.: **29/302,043**

(22) Filed: **Jan. 9, 2008**

(51) **LOC (9) Cl.** **14-03**

(52) **U.S. Cl.** **D14/191**

(58) **Field of Classification Search** **D14/137, D14/155, 159, 191–193, 299, 496; D10/106; 340/7.1, 7.2–7.28, 7.63, 539.13–539.15; 380/31–34, 270, 271; 455/3.01–3.05, 90.1–90.3, 455/95, 128, 347, 351**

See application file for complete search history.
